UNITED STATES PATENT OFFICE

168,645

STEREOSCOPIC VIEWER

John E. Davis, Sherman Oaks, Calif., assignor to
Revere Camera Company, Chicago, Ill., a corporation of Delaware

Application July 28, 1952, Serial No. 20,784

Term of patent 14 years

(Cl. D61—1)

To all whom it may concern:

Be it known that I, John E. Davis, a citizen of the United States, residing at Sherman Oaks, State of California, have invented a new, original, and ornamental Design for a Stereoscopic Viewer, of which the following is a specification, reference being had to the accompanying drawings, forming a part hereof.

Fig. 1 is a plan view of a stereoscopic viewer, showing my design;

Fig. 2 is front elevation thereof;

Fig. 3 is a bottom view thereof; and

Fig. 4 is a side view thereof, the opposite side being substantially identical thereto.

I claim:

The ornamental design for a stereoscopic viewer, as shown.

JOHN E. DAVIS.
